JUMP LEAF EXTENSION TABLE

Frederick B. Walter, Wabash, Ind., assignor to
B. Walter & Company, Inc., Wabash, Ind., a
corporation of Indiana

Application May 18, 1931. Serial No. 538,270

8 Claims. (Cl. 45—112)

The present application relates to jump leaf extension tables. The primary object of the invention is to provide a table of the type which comprises a pair of separable main top sections, 5 and an intermediate top section, in which the intermediate section is normally nested beneath and between the main top sections; the table being so constructed that initial separation of the main sections automatically elevates the intermediate section into the plane of the main sections, after which the main sections may be moved toward each other to form, with said intermediate section, a continuous plane; and that subsequent separation of said main sections will 15 automatically depress the intermediate section, whereafter the main sections may be moved together to return to their initial positions. Further objects of the invention will appear as the description proceeds.

20 To the accomplishment of the above and related objects, my invention may be embodied in the form illustrated in the accompanying drawings, attention being called to the fact, however, that the drawings are illustrative only, and that 25 change may be made in the specific construction illustrated and described, so long as the scope of the appended claims is not violated.

Fig. 1 is a broken side elevation of a table constructed in accordance with the present invention, parts thereof being shown in section;

30 Fig. 2 is a broken bottom plan view of the same;

Figs. 3, 4, and 5 are views similar to Fig. 1, showing the parts in various positions of adjustment;

35 Fig. 6 is an enlarged side elevation of the cam and cam operator, the view being taken from the side opposite that from which Figs. 1 and 3 to 5 are taken; and

40 Fig. 7 is a central longitudinal section through the cam and cam operator, the parts being in the positions shown in full lines in Fig. 6.

Referring more particularly to the drawings, it will be seen that I have illustrated a table top comprising a pair of stationary slide members 10 to which are secured spaced transverse bars 11 and 12. A pair of slides 13 are slidably associated with the stationary members 10, and said slides carry a main top section 14 provided, on its inner edge, with a plurality of dowels 15. The slides 13 co-act with the outer edges of the members 10.

A second pair of slides 16, co-acting with the inner edges of the members 10, carry a second main top section 17, said section being formed

on its inner edge with a plurality of sockets 18 for cooperation with the dowels 15.

One of the slides 16 carries, on its inner surface, a bracket 19 from which a finger 20 projects inwardly for a purpose later to be stated.

60 A pair of upstanding brackets 21 are mounted upon the cross piece 11, and a similar pair of upstanding brackets 22 are mounted on the cross piece 12 in alignment with the brackets 21. A pair of arms or levers 23 have their one ends pivoted to the upper ends of the brackets 21, and a bracing block 24 extends between said arms 23. A pair of short links 25 are pivoted respectively on the upper ends of the brackets 22, and an arm 26 has its one end pivoted to the free 65 end of each of the links 25.

70 A bracket 27 provided at its upper end with a pair of spaced feet 28, is formed at its lower end with a pair of spaced, laterally projecting ears 29 and 30. An ear 31 is carried by one arm 26, and a pin 32 is secured in said ear and carries, at its free end, a contractile spring 33. Means may be provided for adjusting the position of the spring 33 longitudinally of the pin 31. The free end of the spring 33 is anchored on 75 the ear 30, and it is to be understood that, if necessary or desirable, a second spring corresponding to the spring 33 may be anchored to the ear 29 and to an arm 23.

80 One arm 23 is pivoted intermediate its ends, as at 34, to one end of the bracket 27; and one arm 26 is pivoted intermediate its ends, as at 35, to the opposite end of the bracket 27. The projecting ends of said two arms 23 and 26 are pivoted to each other as at 36, relative movement of the two arms 23 and 26 being permitted by the link 25.

85 Pivotedly mounted at 37 on the bracket 27 adjacent the ear 30 is a cam member 38. Referring to Figs. 6 and 7, it will be seen that the member 38 comprises a shell pivotally mounted intermediate its ends on the pivot 37, and formed adjacent its one end with a longitudinally extending slot 39 in which is reciprocably mounted a pin 40. To said pin 40 is secured a plunger 90 41, and an expanding spring 42 is sleeved over said plunger, bearing at its one end against a shoulder 43 on said plunger, and at its opposite end against the end 44 of the shell 38. As will be obvious, the spring 42 urges the pin 40 toward 95 that end of the slot 39 more remote from the pivot 37.

100 Pivotedly mounted at 45 on the bracket 27 adjacent the ear 29 is a cam operator 46. Referring to Figs. 6 and 7 it will be seen that said cam 105

operator 46 comprises a plate having its one end 47 secured to the pin 40. Said plate is mounted intermediate its ends on the pivot 45, and at its opposite end is rebent, as at 48, to provide a lip 49 parallel with the body portion of said operator 46. As is clearly shown in Fig. 6, the lip 49 is shaped to provide a pair of cam surfaces 50 and 51.

The feet 28 of the bracket 27 are secured to 10 the under surface of an intermediate leaf section 52, said section being provided in its one edge with sockets 53 for co-action with the dowels 15, and in its other edge with dowels 54 for co-action with the sockets 18.

15 The top sections 14 and 17 are connected for coordinate movement in a well known manner, as by the provision of a pinion 55 on the element 10 and co-acting racks 56 and 57 on the slides 13 and 16.

20 The normal positions of the parts are illustrated in Fig. 5. If, when the parts are in this position, one of the top sections 14 or 17 is moved outwardly, the other section will be correspondingly moved outwardly through the co-action of 25 the racks 56 and 57 with the pinion 55. As the section 17 moves toward the left, as viewed in Fig. 5, the bracket 19, being carried by one of the slides 16, is correspondingly moved. The lip 49 is positioned, at this time, out of the path 30 of the finger 20, so that said finger 20 passes the cam operator 46 without affecting the same and contacts the adjacent edge surface of the cam 38. Said cam surface is inclined downwardly and to the left so that, as the finger 20 35 moves farther toward the left, the cam 38 is forced upwardly, since rotation of the cam in a counter clockwise direction about its pivot 37 is prevented by the pin 40 which engages said cam and the cam operator 46. As is clearly 40 shown, lines drawn from the pin 40 to the pivot 37 and to the pivot 45 are, when the parts are positioned as in Fig. 5, substantially perpendicular to each other.

The arms 23 and 26 being secured to the bracket 27 will be moved, respectively, in clockwise and counter clockwise direction, the spring 33 assisting in this movement, the strength of said spring being such as substantially to counterbalance the weight of the leaf 52. The parts are 45 so arranged and proportioned that, when the limit of movement of the section 17 is reached, the finger 20, in cooperation with the cam 38, will have moved the associated parts into the 50 position of Fig. 1, wherein the section 52 is disposed in the plane of the sections 14 and 17.

55 The sections 14 and 17 may now be moved toward each other, the leaf 52 being held in position by the spring 33. As said sections are so moved, the finger 20 comes into contact with the face 51 of the lip 49. Further movement of the finger 20 in unison with the section 17 will cause the cam operator 46 to be oscillated in a counter clockwise direction about its pivot 45, compressing the spring 42. As the dowels 15 60 and 54 enter the sockets 53 and 18, the cam operator is moved beyond its dead-center position with respect to the cam 38, and the spring 42 expands to move the cam and cam operator into the positions illustrated in Fig. 3. A slight 65 further movement then brings the table top sections into position to form a single, extended plane surface.

70 When the table top sections 14 and 17 are again separated, the finger 20 contacts the opposite side surface of the cam 38, which is now

inclined upwardly and to the left, as viewed in Fig. 3, to depress the section 52, the spring 33 being extended as the depression of the section 52 is completed, the arms 23 and 26 guiding the movement of said section. As the sections 14 and 17 are again moved toward each other, the finger 20 contacts the face 50 of the cam operator 46 to rotate said operator in a clockwise direction about its pivot 45, whereby the parts are returned to the positions of Fig. 5.

I claim as my invention:

1. A jump leaf table comprising a base, a pair of main top sections mounted on said base, said sections being relatively laterally movable, an intermediate top section, means guiding said intermediate top section for vertical movement into and out of the plane of said main sections, and automatic means for shifting said intermediate section into and out of said plane alternatively upon successive separations and reunions of said main sections, said last-named means comprising a finger shiftable with one of said main sections, and cam mechanism shiftable with respect to said intermediate section and cooperable with said finger.

2. A jump leaf table comprising a base, a pair of main top sections mounted on said base, said sections being relatively laterally movable, an intermediate section, means guiding said intermediate section for vertical movement into and out of the plane of said main sections, means cooperable with said guiding means for counterbalancing the weight of said intermediate section, and automatic means for shifting said intermediate section into and out of said plane alternatively upon successive separations and reunions of said main sections, said last-named means comprising a finger shiftable with one of said main sections, and shiftable cam mechanism solely supported on said intermediate section and cooperable with said finger.

3. A jump leaf table comprising a base, a pair of main top sections mounted on said base, said sections being relatively laterally movable, an intermediate section, means guiding said intermediate section for vertical movement into and out of the plane of said main sections, and automatic means for shifting said intermediate section into and out of said plane alternatively upon successive separations and reunions of said main sections, said last-named means comprising a finger shiftable with one of said main sections, and a cam solely supported on said intermediate section and engageable by said finger, as said main sections are separated, to shift said intermediate section.

4. A jump leaf table comprising a base, a pair of main top sections mounted on said base, said sections being relatively laterally movable, an intermediate section, means guiding said intermediate section for vertical movement into and out of the plane of said main sections, and automatic means for shifting said intermediate section into and out of said plane alternatively upon successive separations and reunions of said main sections, said last-named means comprising a finger shiftable with one of said main sections, a cam carried by said intermediate section and engageable by said finger, as said main sections are separated, to shift said intermediate section, and a cam operator associated with said cam and engageable by said finger, as said main sections are reunited, to shift said cam.

5. A jump leaf table comprising a base, a pair of main top sections mounted on said base, said

- sections being relatively laterally movable, an intermediate section, means guiding said intermediate section for vertical movement into and out of the plane of said main sections, and automatic means for shifting said intermediate section into and out of said plane alternatively upon successive separations and reunions of said main sections, said last-named means comprising a finger shiftable with one of said main sections, a cam element pivoted intermediate its ends on said intermediate section, and a cam operator pivoted intermediate its ends on said intermediate section and having one end pivotally associated with an end of said cam, said cam and cam operator being positioned for cooperation with said finger whereby, as said main sections are moved apart, said finger passes said cam operator and engages said cam to elevate said intermediate section; as said main sections are subsequently moved toward each other, said finger engages said cam operator to shift said operator and said cam about their pivots on said intermediate section; as said main sections are again moved apart, said finger again passes said cam operator and engages said cam to depress said intermediate section; and as said main sections are again moved toward each other, said finger engages said cam operator to return said operator and cam to their initial positions.
6. A jump leaf table comprising a base, a pair of main top sections mounted on said base, said sections being relatively laterally movable, an intermediate section, means guiding said intermediate section for vertical movement into and out of the plane of said main sections, and automatic means for shifting said intermediate section into and out of said plane alternatively upon successive separations and reunions of said main sections, said last-mentioned means comprising a finger shiftable with one of said main sections, a cam element pivoted intermediate its ends on said intermediate section, a cam operator pivoted intermediate its ends on said intermediate section and having one end pivotally associated with one end of said cam element, whereby said cam and cam operator are dependently shiftable through approximately 90° about their respective pivots, said cam and operator being positioned for cooperation with said finger, and being so associated that, in either of their extreme positions, lines drawn from the point of connection between said elements to their respective pivots are substantially perpendicular, and means resiliently holding said cam and operator in either of their extreme positions.
7. A jump leaf table comprising a base, a pair of main top sections mounted on said base, said sections being relatively laterally movable, an intermediate section, means guiding said intermediate section for vertical movement into and out of the plane of said main sections, and automatic means for shifting said intermediate section into and out of said plane alternatively upon successive separations and reunions of said main sections, said last-named means comprising a finger shiftable with one of said main sections, a cam element pivoted intermediate its ends on said intermediate section, a cam operator pivoted intermediate its ends on said intermediate section and having one end pivotally associated with one end of said cam element, whereby said cam and cam operator are dependently shiftable through approximately 90° about their respective pivots, said cam and operator being positioned for cooperation with said finger, and being so associated that, in either of their extreme positions, lines drawn from the point of connection between said elements to their respective pivots are substantially perpendicular, and means resiliently holding said cam and operator in either of their extreme positions.
8. A jump leaf table comprising a base, a pair of main top sections mounted on said base, said sections being relatively laterally movable, an intermediate section, means guiding said intermediate section for vertical movement into and out of the plane of said main sections, and automatic means for shifting said intermediate section into and out of said plane alternatively upon successive separations and reunions of said main sections, said last-named means comprising a finger shiftable with one of said main sections, a cam element pivoted intermediate its ends on said intermediate section, said element being formed, adjacent one end, with a longitudinally extending slot, a pin mounted for movement in said slot, spring means urging said pin toward the end of said slot remote from the pivot of said element, and a cam operator pivoted intermediate its ends on said intermediate section and having one end connected to said pin, said cam and operator being positioned for cooperation with said finger.
